UNITED STATES PATENT OFFICE.

EDGAR CHERRY, OF SAN FRANCISCO, CALIFORNIA.

ADVERTISING DEVICE.

SPECIFICATION forming part of Letters Patent No. 640,875, dated January 9, 1900.

Application filed June 5, 1899. Serial No. 719,506. (No model.)

To all whom it may concern:

Be it known that I, EDGAR CHERRY, a citizen of the United States, residing at San Francisco, in the county of San Francisco and State 5 of California, have invented certain new and useful Improvements in Advertising Devices; and I do hereby declare the following to be a full, clear, and exact description of said invention, such as will enable others skilled in 10 the art to which it most nearly appertains to make, use, and practice the same.

This invention relates particularly to rotating mechanisms adapted to the actuation of advertising devices, for which Letters Patent 15 of the United States were granted to me on the 4th day of April, 1899, bearing No. 622,416, and will be described in connection therewith.

The object of the present invention is to provide automatic and simple means for rotating a wheel one-half revolution forward 20 and back.

In the drawings, Figure 1 is a front elevation of an advertising device constructed in accordance with this invention, being partly 25 broken away to show the operating mechanism. Fig. 2 is a side elevation of the operating mechanism. Fig. 3 is a front elevation of the same.

The advertising feature of the device consists 30 of a series of panels so connected together that a half-revolution of the end panel or the one designated in the drawing Fig. 1 as No. 1 will lift No. 2 to a position directly behind No. 1, when by the action of gravity and the peculiar 35 hangings 2 will fall to a position behind 3, 3 will fall out over 4, 4 behind 5, and so on through the series, which may comprise any number of panels. In the reverse rotation of the panel No. 1 will resume its former position, drawing 2 up in front of it, repeating 40 the former action, but exposing the reverse side of each panel which has shown in the rear of the device in an inverted position.

The present invention for producing the 45 above effects, described with reference to the drawings, consists of a sprocket-chain, (designated by the distinguishing-letter A,) the sprocket-wheels A' A², the actuating means therefor, such as the motor B, and the sheave- 50 pulleys C and D, the former, C, engaging the sprocket-chain A by means of the pins A³

thereon and the pins C' extending in a peripheral arc one-half the circumference of and alined on both sides of the sheave C, the latter, D, repeating the rotations of the former by reason of the belt connection E between them. 55

The motive power B is shown as an electric motor, it being obvious, however, that this may be substituted by a spring-motor, water-wheel, or any other suitable means. 60

The motor B actuates the sprocket-wheel A' through the reducing-gears B' B², the sprocket A' transmitting motion to the chain A, the pins A³ thereon engage the pins C' successively, giving a one-half rotation to the 65 pulley C, the chain, continuing over the wheel A², returns, the pins A³ engaging the pins C' on the opposite side of the pulley C rotate it backward to the normal position, one revolution of sprocket-chain A causing the exposure 70 of both sides of each panel in the series, it being evident, however, that more than one series of pins A³ may be used to cause, if desired, quicker changes in the panels.

I have found it preferable to locate the actuating mechanism at the side of the device, as shown; but it may be, with a few slight changes, located horizontally across the top 75 of the frame X and geared to the pulley D by means of a miter-gear without altering the 80 spirit of this invention.

The panel No. 1 is secured to the pulley D by means of the socket D' on the face of said pulley, the other end of said panel being pivoted upon a pin extending from the end of 85 said panel engaging a socket on the side of the frame X. This socket D' facilitates the removal and change of the series of panels.

The pulley C and belt E may be dispensed with by placing the pins C' in the pulley D; 90 but this would necessitate the raising of the sprockets A' and A², so as to time the changes of the panels equally, and detract from the appearance of the machine.

When the sheave C and belt E are dispensed 95 with, the structure may be simplified by reducing the circumference of the pulley D to just sufficient to accommodate the pins C'.

Having thus described this invention, it is claimed— 100

In a mechanism such as described, the combination with a wheel having pins extending

in a peripheral arc, one-half the circumference of, and alined on both sides of the said wheel; an endless sprocket-chain having a series of pins extending therefrom, and adapted to engage the pins on the wheel, said sprocket-chain so mounted that its direction of motion carries the series of pins thereon upward on the one side, and downward on the opposite side of the said wheel; and an actu-

ating mechanism for said sprocket-chain, substantially as described.

In testimony whereof I have hereunto set my hand this 18th day of May, 1899.

EDGAR CHERRY.
